F. R. CHILDREN.

HOG OILER.

APPLICATION FILED APR. 19, 1915.

1,241,495.

Patented Oct. 2, 1917.

UNITED STATES PATENT OFFICE.

FRANK R. CHILDREN, OF COUNCIL BLUFFS, IOWA, ASSIGNOR TO E. CHILDREN'S SONS
MANUFACTURING CO., OF COUNCIL BLUFFS, IOWA, A CORPORATION OF IOWA.

HOG-OILER.

1,241,495.

Specification of Letters Patent.

Patented Oct. 2, 1917.

Application filed April 19, 1915. Serial No. 22,289.

To all whom it may concern:

Be it known that I, FRANK R. CHILDREN, a citizen of the United States, residing in Council Bluffs, in the county of Pottawattamie and State of Iowa, have invented a new and useful Improvement in Hog-Oilers, of which the following is a specification.

My invention relates in general to hog oilers and has more particular reference to devices of this character arranged to cause an automatic application of oil or other medicament whenever a hog rubs thereagainst.

The purpose of a device of this character is, generally speaking, the application of oil or the like to a hog for the killing of lice and other vermin. The intention is that a hog shall rub against a member provided for the purpose with the result that oil will be delivered upon him, this oil being delivered in sufficient quantity to cover an appreciable portion of the skin surface.

A principal object of the invention is the provision of such a device which will permit the hog to rub his back as well as his sides thereagainst, so that the oil may run down over his flanks and on to his legs and under his belly.

A further object of the invention is the provision of such a device which will insure a maximum effect through the utilization of a minimum amount of vermin exterminating material.

A further object of the invention is the provision of means for varying the amount of oil delivered to suit changes of fluidity resulting from seasonal differences in temperature.

A further object of the invention is the provision of such a device which will be of economical manufacture, the parts of which will not be readily damaged or disarranged under the rough usage ordinarily given such devices.

Other objects and advantages of the invention will be apparent as it is better understood from the following description when considered in connection with the accompanying drawing illustrating a preferred embodiment thereof.

On the drawing,

Figure 1 is a side elevation of a hog oiler embodying my invention;

Fig. 2 is a longitudinal partial section through the same;

Fig. 3 is a section taken substantially on the line 3—3 of Fig. 2;

Fig. 4 is a similar view taken substantially on the line 4—4 of Fig. 2;

Fig. 5 is a side elevation of the mounting for the oiler; and

Fig. 6 is a perspective view of the valve operating lever provided in the present instance.

The hog oiler shown on the drawing and embodying my invention comprises a supporting base 7 in which is secured a stationary shaft 8 carrying, at its upper end, a reservoir 9 for the containing of oil or other vermin exterminating material. A member 10 against which the hog may rub in the present instance embraces the shaft 8 and this member, when the hog rubs thereagainst, operates a lever 11 controlling a delivery valve 12.

The support 7 is provided with a base plate 13 which may be secured to any suitable permanent support 14 by bolts 15 or the like. It provides an inclined socket 16 in which is secured an end 17 of the shaft 8, thus disposing the shaft 8 in inclined position. The inclination, about forty-five degrees, given this shaft is sufficient to bring it well over the back of the hog and the length of the shaft is sufficient to permit the hog to get well under it when he rubs thereagainst. The upper end of the shaft 8 is threaded at 19 and is engaged in an inclined socket 21 formed in the base of the reservoir 9, the inclination of this socket being such that the reservoir 9 maintains the upright vertical position shown.

The rubbing member 10 in the present instance consists of a sleeve having an internal diameter much greater than the external diameter of the shaft 8. This sleeve loosely embraces the shaft and is movable in several directions when a hog rubs thereagainst, being held by gravity in the position shown in Fig. 1 and being capable of being moved laterally by rocking or by a straight rear movement, and being capable also of moving upwardly along the shaft. Its outer surface is roughened in order that effective scratching of the back of the hog as well as oiling may be accomplished. This is de-

sirable as it removes considerable dirt and exposes the vermin to the oil which is applied, as will be later described. It also provides a pleasing sensation to the hog and encourages him to make use of the oiler.

Any movement of the sleeve 10 causes an operation of the lever 11 which in turn operates the valve 12. This lever consists of a bifurcated end forming arms 22 adapted to be disposed upon opposite sides of the lug 23. The arms 22 are perforated and are pivotally secured to the lug 23 by a pivot pin 24. The forward end of the lever is flat and curved downwardly at 25 to rest upon the sleeve 10, the lower extremity of the lever being cut away arcuately at 26 to maintain it in engagement with the sleeve. It will be manifest that any lateral movement of the sleeve will operate the lever by pressing against it and upward or longitudinal movement will produce like results through engagement of the lever with the end of the sleeve or by the engagement with the roughened surface of the sleeve.

25. In order that a predetermined quantity only of oil may be delivered to the hog, the valve 12 is given the peculiar construction to be now described. A valve casing 27 is screwed into the bottom of the reservoir 9, this casing having at its top a valve seat 28 beneath which a port 29 is provided. This port communicates with an enlarged chamber 30 immediately therebeneath, the chamber 30 extending to and through the lower end of the casing. A valve member is positioned in this casing and this valve member comprises two valve heads 31 and 35 adapted to seat respectively against the seat 28 and the lower end of the casing 27. The upper valve head 31 is provided with a fluted stem portion 32 which permits passage of the liquid through the port 29 and also with a threaded portion 34 on which is engaged the valve head 35, also having a fluted stem 36 movable in the chamber 30, this stem providing passageways 38. The head 35 is adapted to seat against the lower end of the valve casing to close the reservoir when the valve is raised to its upper limit. A spring 39 is positioned between the upper end of the chamber 30 and the upper end of the valve stem 36, normally holding the valve in lower position. The lower end of the portion 34 of the valve stem is engageable by the head of a bolt 41 adjustably secured in an aperture 42 in the lever 11, upward

movement of the lever bringing the head of the bolt 41 into engagement with the lower end of the threaded portion 34 of the valve stem, thereby lifting the lower valve head 35 and the upper valve 31 and permitting a discharge of oil which flows downwardly through the passages 33, through the chamber 30, through the passages 38 and on to the wide end 25 of the lever, off which it flows either on to the hog or on to the sleeve 10 and thence on to the hog. This causes a limited and predetermined amount of oil to be delivered and thereby prevents an overdischarge of oil should the hog occupy a lengthened period in rubbing against the member or sleeve 10. The bolt 41 may be turned to produce a proper delivery in both cold and hot weather and in accordance with the relative fluidity at these times.

It will be manifest that the device consists of few and simple parts which may be cheaply provided and which, when properly assembled, provide little opportunity for the need of repair.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a hog oiler, an inclined member so arranged that an animal can rub its back, sides, and belly on appropriately presented portions of it and means for conveying oil to every said portion of said member.

2. A hog oiler comprising a support and a laterally movable and rotatable member loosely surrounding the same and against which the hog may rub and sufficiently inclined to admit of the animal bringing substantially all portions of its body in contact therewith, a reservoir for delivering oil to said member and a valve member operable by lateral movement of said member for delivering a quantity of oil.

Signed in the presence of two subscribing witnesses.

FRANK R. CHILDREN.
